UNITED STATES PATENT OFFICE.

OLIN II. BASQUIN, OF CHICAGO, ILLINOIS, ASSIGNOR TO THE LUXFER PRISM PATENTS COMPANY, OF SAME PLACE.

DESIGN FOR A PRISM-PLATE.

SPECIFICATION forming part of Design No. 27,343, dated July 13, 1897.

Application filed June 15, 1897. Serial No. 640,917. Term of patent 14 years.

To all whom it may concern:

Be it known that I, OLIN II. BASQUIN, a citizen of the United States, residing at Chicago, in the county of Cook and State of Illinois, 5 have invented and produced a certain new and useful Design for Prism-Plates, of which the following is a description.

My invention relates to a design for prism-plates.

10 It is illustrated by the accompanying drawing, wherein—

A is a prism-light having thereon a series of prisms B B, the several prism-lights surrounded by a frame C and separated from 15 each other by the inner frame-pieces D D.

The essential feature of my design for a prism-plate is the representation of several prism-lights assembled together in the form of a prism-plate, separated by opaque strips and provided each with a series of prisms 20 which extend diagonally across such lights, as shown.

I claim—

The design for a prism-plate substantially as shown and described.

OLIN II. BASQUIN.
